(57) **CLAIM**

The ornamental design for a torpedo shape remote control holder, substantially as shown in the attached drawings.

DESCRIPTION

FIG. 1 is a perspective view of the torpedo shape remote control holder, with a lid that opens and closes (shown

closed), wherein remote control devices which do not form part of the design are shown in phantom as these may be positioned in each of four pockets of the torpedo shape remote control holder;

FIG. 2 is a front plan view corresponding to FIG. 1;

FIG. 3 is a rear plan view corresponding to FIG. 1;

FIG. 4 is a top side plan view corresponding to FIG. 1, wherein the logo does not form part of the design and therefore is shown in phantom;

FIG. 5 is a left side plan view corresponding to FIG. 1 (with right side and bottom views being the same), wherein a hook-and-loop or VELCRO® fastener does not form part of the design and therefore is shown in phantom;

FIG. 6 is a perspective view of the torpedo shape remote control holder with the lid that opens and closes (shown open to reveal a storage area inside the torpedo shape remote control holder);

FIG. 7 is a front plan view corresponding to FIG. 6;

FIG. 8 is a rear plan view corresponding to FIG. 6;

FIG. 9 is a right side plan view corresponding to FIG. 6;

FIG. 10 is a left side plan view corresponding to FIG. 6;

FIG. 11 is a top plan view corresponding to FIG. 6 (with bottom view being a mirror image);

FIG. 12 is a cross sectional view taken through line 12-12 of FIG. 4 showing the top/left perspective view corresponding to FIG. 1 and showing a cylindrical storage area inside the torpedo shape remote control holder;

FIG. 13 is a cross sectional view taken through line 13-13 of FIG. 4 showing the bottom/right perspective view corresponding to FIG. 1 showing the cylindrical storage area inside the torpedo shape remote control holder;

FIG. 14 is a cross sectional view taken through line 14-14 of FIG. 4 showing the top/left perspective view corresponding to FIG. 1 showing an alternative rectangular storage area inside the torpedo shape remote control holder; and,

FIG. 15 is a cross sectional view taken through line 15-15 of FIG. 4 showing the bottom/right perspective view corresponding to FIG. 1 showing the rectangular storage area inside the torpedo shape remote control holder.
